CLAIM

I claim the ornamental design of a direct current power supply, as shown and described.

DESCRIPTION

FIG. 1 is a perspective view of the direct current power supply;

FIG. 2 is a front view of the direct current power supply, the back view being a mirror image the front view;

FIG. 3 is a bottom view of the direct current power supply; FIG. 4 is a top view of the direct current power supply; and, FIG. 5 is a right side view of the direct current power supply, the left side view being a mirror image the right side view.

The broken lines shown are for illustrative purposes only and form no part of the claimed design.

The broken lines which define the bounds of the claimed design form no part thereof.
